UNITED STATES PATENT OFFICE.

GEORGE W. NELSON, OF CLEVELAND, OHIO, ASSIGNOR TO THE STANDARD SEWING MACHINE COMPANY, OF CLEVELAND, OHIO, A CORPORATION OF OHIO.

SEWING-MACHINE.

1,228,125.

Specification of Letters Patent.

Patented May 29, 1917.

Application filed December 7, 1915. Serial No. 65,479.

To all whom it may concern:

Be it known that I, GEORGE W. NELSON, a citizen of the United States, and resident of Cleveland, in the county of Cuyahoga and 5 State of Ohio, have invented certain new and useful Improvements in Sewing-Machines, of which the following is a specification.

My invention relates to improvements in 10 sewing machines and more particularly to sewing machines of the rotary hook type, such, for example, as shown in Letters Patent No. 1,005,250, dated October 10, 1911.

The main object of my invention is to facilitate the handling of the hook and associated parts, such as the bobbin, bobbin-case, 15 and bobbin-case latch, both in their removal from and replacement in the machine, and also in their adjustment relative to coöperating parts of the machine. This object I accomplish by adapting and combining the 20 said several parts for unitary handling and adjustment.

The invention is illustrated in the accompanying drawings, in which—

25 Figure 1 is a bottom plan view of a sewing machine embodying my invention, and

Fig. 2 is a side view of the construction shown in Fig. 1, partly broken away and in section.

30 As my invention relates only to the hook and associated parts located at the under side of the bed-plate of the machine, I have limited the illustration of the machine accordingly.

35 As shown, 1 indicates the bed-plate, 2 the hook shaft carrying at its front end the attached hook 3, and 4 the drive belt engaging a sprocket wheel on the rear end of the drive shaft.

40 The shaft 2 is supported adjacent its opposite ends in bushed bearings 5 and 6, which bearings as here shown are formed in a supporting bracket 7 detachably and adjustably connected to the bed-plate in substantially the same manner as disclosed in 45 the aforesaid Patent No. 1,005,250. So far as my present invention is concerned, however, the shaft 2 might be supported in bearings formed or otherwise located at the under side of the bed-plate in any suitable or desired manner.

50 In accordance with my invention, the shaft 2 is transversely divided between its end bearings, as indicated at 8, whereby the front end thereof with its attached hook

may be readily removed from the machine without disturbing the connection of the rear end with the shaft driving means. As a means for operatively coupling the shaft ends or sections to permit of such disconnection of the same, I have attached sleeves 9, 9, to the adjacent ends of the shaft sections having overlapping ends 10, 10, which coöperate to couple the shaft sections for rotary movement and which also permit of the front 65 section being adjusted longitudinally of the rear section for the purpose of positioning its attached hook relative to the vertical path of the needle n.

The bushing 11 of the bearing 5 is provided at its front end with a bracket 12 having two forwardly projecting arms 13, 13, to which is pivotally connected a latch 14 for holding the bobbin-case 15 and its contained bobbin 16 in operative position within 70 the hook. A spring catch 17 for holding the latch 14 in closed position is also carried by the bracket 12, being connected thereto at 75 18. The bushing 11, carrying by its bracket 12 the complete bobbin-case latch device, is 80 connected longitudinally with the hook-carrying section of the shaft 2 journaled therein, by the engagement of its opposite ends with shoulders on said shaft, one shoulder being provided by the hub 19 of the hook 85 and the other shoulder being provided by the coupling sleeve 9, as shown.

The bushing 11, with its connected parts as described, is removably and adjustably held within the bearing 5 by suitable fastening means. These fastening means as here shown, comprise a set-screw 20 carried by the bracket 7 for engaging the bushing to hold it against longitudinal movement, and an adjusting screw 21 also carried by the 90 bracket 7 for engaging the bushing bracket 12 within a seat 22 therein to hold the bushing against rotary or turning movements in its support. This screw 21, by endwise adjustment, also serves to position the parts whereby the hook will be brought in proper relation to the path of the needle.

By dividing the hook shaft in a manner to render it both extensible and separable, and combining as a single unit the front shaft section and bushing with their supported parts, comprising the hook, bobbin, bobbin-case, and bobbin-case latch, in the manner shown and described, it enables the several parts comprised in such unit, after being 105 110

once properly adjusted to their position in the machine by the setting of the adjusting screw 21, to be removed from and replaced in the machine as often as desired without 5 further readjustment, and also enables the hook and associated parts to be adjusted as a unit relative to the needle without in any way disturbing the adjustment of those parts relative to each other.

10. What I claim is:—

1. In a sewing machine, the combination with a reciprocating needle, of a bed-plate having a support at its under side, a bushing carried by said support and longitudinally adjustable in a direction toward and from the needle path, a shaft having an attached hook journaled in said bushing and a bobbin-case latch connected to the bushing independently of said hook and 15 both the shaft and the latch being adjustable with the bushing, and means for adjustably holding the bushing in a longitudinally stationary position.

2. In a sewing machine, the combination with a reciprocating needle, of a bed-plate having a support at its under side, a bushing carried by said support and longitudinally adjustable in a direction toward and from the needle path and having a latch- 20 supporting bracket at that end adjacent the needle path, a shaft having an attached hook journaled in said bushing and a bobbin-case latch connected to said supporting bracket and both being adjustable with the bushing, and means for adjustably holding the bushing in a longitudinally stationary position.

3. In a sewing machine, the combination with a bed-plate having a support at its 25 under side, of a bushing removably connected with said support, and a drive shaft having an attached hook, a bobbin, a bobbin case, and a bobbin-case latch, all carried by said bushing and removable there- 30 from the bed-plate support, the said bobbin-case latch being mounted on the bushing independently of the hook.

4. In a sewing machine, the combination with a bed-plate having a support at its 35 under side formed with an opening extending lengthwise of the bed-plate, of a bushing adjustably and removably seated in said opening, a drive shaft having an attached hook, a bobbin, a bobbin-case, and 40 a bobbin-case latch, all carried by said bushing for adjustment and movement therewith, the said bobbin-case latch being mounted on the bushing independently of the hook, and means for holding the bushing and supported parts in adjusted position.

5. In a lock-stitch sewing machine, the combination with a reciprocating needle, of a bed-plate having bearings at its under 45 side one of which comprises a longitudi-

nally adjustable bushing, a sectional drive shaft supported in said bearings and being extensible in the direction of its length and carrying a hook and bobbin at the end thereof adjacent the needle path, that part 70 of the shaft carrying the hook being connected with the bushing for longitudinal adjustment therewith, and means for adjustably holding the bushing in a longitudinally stationary position.

75

6. In a lock-stitch sewing machine, the combination with a reciprocating needle, of a bed-plate having bearings at its under side, a drive shaft supported in said bearings and carrying a hook and bobbin at its 80 forward end, said shaft being transversely divided between its ends and coupled by means permitting of the free endwise withdrawal of the hook-carrying end from the opposite or rear end, and means adjustably 85 holding the hook-carrying end of the shaft in a longitudinally stationary position relative to the needle path.

7. In a lock-stitch sewing machine, the combination with a reciprocating needle, 90 of a bed-plate having bearings at its under side, a drive shaft supported in said bearings and carrying a hook and bobbin at its forward end, said shaft being transversely divided between its ends and connected by 95 a split coupling permitting of the free endwise withdrawal of the hook-carrying end from the opposite or rear end, and means adjustably holding the hook-carrying end of the shaft in a longitudinally stationary 100 position relative to the needle path.

8. In a lock-stitch sewing machine, the combination with a reciprocating needle, of a bed-plate having bearings at its under side one of which comprises a longitudinally adjustable bushing, a drive shaft supported in 105 said bearings and carrying a hook and bobbin at its forward end, said shaft being transversely divided between its ends and connected by a split coupling permitting of 110 the free endwise withdrawal of the hook-carrying end from the opposite or rear end, means connecting the hook-carrying end with the bushing for longitudinal adjustment therewith, and means adjustably holding the bushing in a longitudinally stationary 115 position.

9. In a lock-stitch sewing machine, the combination with a reciprocating needle, of a bed-plate having a support at its under 120 side, a bushing removably connected with said support, a drive shaft having an attached hook, a bobbin, a bobbin-case, and a bobbin-case latch, all carried by said bushing and removable therewith from the bed-plate 125 support, the said bobbin-case latch being mounted on the bushing independently of the hook, adjustable means for determining the position of the bushing and its supported parts relative to the needle path, and 130

means for adjustably holding the bushing in a longitudinally stationary position.

10. In a lock-stitch sewing machine, the combination with a reciprocating needle, of a bed-plate having a support at its under side, a bushing removably connected with said support, a drive shaft having an attached hook, a bobbin, a bobbin-case, and a bobbin-case latch, all carried by said bushing and removable therewith from the bed-plate support, the said bobbin-case latch being mounted on the bushing independently 15 of the hook, an adjustable stop on the support for engaging with a part of the bushing and determining the position of the latter and its associated parts relative to the needle path, and means for holding the bushing and associated parts in adjusted position.

11. In a lock-stitch sewing machine, the combination with a reciprocating needle, of a bed-plate having a support at its under side, a bushing removably connected with said support and having a latch-supporting bracket at one end thereof, a hook drive-shaft journaled in said bushing and a bobbin-case latch pivoted to the bracket on said bushing, an adjusting screw on the support engaging the bushing bracket to adjustably 25 position the bushing and associated parts

relative to the needle path, and means for holding the bushing and associated parts in adjusted position.

12. In a lock-stitch sewing machine, the combination with a bed-plate having a support at its under side, of a bushing longitudinally adjustable in said support, a hook shaft journaled in said bushing, a hook on said shaft, a bobbin-case supported in the hook, and a bobbin-case latch attached to the bushing independently of the hook end and 35 adjustable therewith.

13. In a lock-stitch sewing machine, the combination with a bed-plate having a support at its under side, of a bushing longitudinally adjustable in said support and 45 having at its front end a projecting latch-supporting bracket, a hook shaft journaled in said bushing, a hook on said shaft, a bobbin-case supported in the hook, and a bobbin-case latch attached to and supported 50 by the bushing bracket.

Signed at Cleveland, in the county of Cuyahoga, and State of Ohio, this 2d day of December, A. D. 1915.

GEORGE W. NELSON.
